UNITED STATES PATENT OFFICE

MORRIS C. KNIGHT, OF ALEXANDRIA BAY, NEW YORK

ICE AND WATER BOAT

Application filed May 21, 1928, Serial No. 279,484. Renewed May 29, 1931.

This invention relates to a new and improved combined ice and water vehicle.

In a great many parts of the country during a considerable portion of each year it is very desirable to have a vehicle which can be mechanically propelled on the surface of ice as during a considerable period of the year the lakes and rivers are frozen over. At other periods of the year and in the same locality it is necessary to have vehicles which can be propelled on and through the water.

At those sections of the country where the water courses are frozen over during certain portions of the year there is a time at the beginning of winter and also a time at the end of winter when the water courses are only partially frozen over. When this condition exists where part of a water course is covered with ice and where another part is not covered with ice or is covered only with ice which is not sufficiently thick and strong to support the weight of a vehicle, a vehicle which is constructed for movement over ice only is impractical as is a vehicle which is constructed for propulsion on the water only.

The condition just described where a water course is partially frozen and partially not usually exists for a considerable length of time in the aggregate during each year with the result that vehicles can not be used to cross such water courses and there is a considerable time when direct communication from shore to shore can not be had.

I am aware that vehicles have been constructed for propulsion on ice and also that vehicles have been constructed for propulsion on ice in which the motive power consisted of a mechanically driven air propeller.

I am also aware that boats for use on the water have heretofore been propelled by air propellers. I am also aware that boats which were primarily designed for use in water have been equipped with runners so that they could be propelled on the ice but so far as I am aware no vehicle has ever been constructed which could, without any mechanical changes, be used for transportation whether on ice or on the water or which could, without any interruption of its forward move-

ment, pass from the water onto the ice and vice versa.

The advantage of a vehicle which can be used on water courses irrespective of whether they are covered with ice or partially covered with ice or on which no ice is present is obvious for it furnishes an uninterrupted means of transportation from shore to shore of a water course irrespective of the presence or absence of ice, and the main object of my invention is to construct a device which may be propelled on the water or on the ice.

Another object is to construct a device which can be used in the manner just described without the necessity of any mechanical changes in the structure to adapt it for use on either ice or water.

Other objects and advantages relate to the size, shape and association of parts all as will more fully appear from the following description taken in connection with the accompanying drawings in which:—

Figure 1 is a perspective view of my combined ice and water vehicle.

Figure 2 is a section on line 2—2 of Figure 1.

Figure 3 is a section on line 3—3 of Figure 2.

Figure 4 is a section on line 4—4 of Figure 2.

Figure 5 is a section on line 5—5 of Figure 2.

My device consists of a hollow substantially rectangular body —1— having its bottom portion curved upwardly at the forward end as indicated at —a— in Figure 2. The base on body portion —1— is preferably made of strong construction and I have here shown a bottom plate —2— with a plurality, in this case shown as sixteen, of transversely extending ribs —3— with a second or false bottom —4— superimposed on the upper faces of ribs —3—. On the central portion of the top of body —1— I provide a vertically extending case or cabin —5— preferably having windows as —6— on the side, front and back. For a purpose hereinafter to be described I provide a flat top —7— extending from the rear end of cabin —5— to the rear end of body —1— to form an open deck

—8—. On the opposite longitudinal edges of the under portion of body —1— I provide parallel spaced runners —9— and —10— preferably made of steel or iron and of a thickness sufficient to raise the under portion of the vehicle from the ice. Runners —9— and —10— are also preferably narrow so as to minimize the friction between them and the ice.

10 As perhaps may best be seen from Figure 3 the front end —11— of the vehicle is wider than the rear end —12— so that when the vehicle is traveling through ice which is not thick enough to sustain its weight so that 15 the vehicle breaks through the ice and makes a path for itself in the water the path made by the front end —11— will be wider than the width of the rear end —12— to permit lateral movement of the rear end for the purpose of guiding it in the desired direction.

20 On the rear deck —8— of the vehicle I position an airplane type engine —13— having the usual air propeller —14— and supported in position by an appropriate framework as —15—. The propeller —14— is positioned so that its thrust on the air is toward the rear of the vehicle so that when the propeller is revolving it will force the vehicle forward. Immediately in the rear of propeller —14— I provide an air rudder —16— having its top end journaled in a bracket —17— and having its lower end journaled in a bearing —18— affixed to the center of the rear end —12— of the vehicle. The rudder —16— has affixed, adjacent its rear end, opposed steering cables —19— and —20—. Cable —19— extends laterally from rudder —16— into a sheave —21— positioned at one end of rear end —12— of the vehicle. Cable —19— passes from sheave —21— through an aperture —22— into the vehicle and thence to a position adjacent the forward end —11— where it passes around a sheave —23— and thence to a drum —24— journaled in brackets —25— and —26— positioned on false bottom —4—. Similarly cable —20— passes around a sheave —27— and thence to a position adjacent the forward end —11— to and around a sheave —28— which is positioned in opposed relation to sheave —23— and from sheave —28— to and around drum —24—.

25 The rear end of drum —24— is provided with a bevel gear —29— in mesh with a second bevel gear —30— affixed to the end of a steering post —31— journaled in bracket —26—. The rear end of steering post —31— carries a steering wheel —32—. It will be understood that the rotation of steering wheel —32— through steering post —31— and bevel gears —30— and —29— will transmit rotary motion to drum —24— and will cause cables —19— and —20— to be either wound on or unwound from drum —24— depending upon the direction of ro-

tation of drum —24—. The movement of cables —19— and —20— onto and from drum —24— will cause rudder —16— to be moved laterally. The direction of such lateral movement will be determined by the direction of rotation of drum —24—.

For the purpose of retarding the forward movement of the vehicle when it is traveling on the ice I provide a pair of opposed drags —33— and —34—. The construction of drags —33— and —34— is the same so that a description of one will be a description of both. Drag —33— comprises a drag arm —35— secured to a shaft —36— journaled on a side —37— of body —1—. Shaft —36— has on its inner end a crank arm —38—. The length of drag arm —35— in relation to its position in side —37— is such that when it is in the lowered position it will extend beneath the runner —10— and contact with the ice on which the vehicle is moving. In the forward end of the vehicle I provide a laterally extending shaft —39— having one end journaled in a bearing —40— positioned in side —37—. The other end of shaft —38— is journaled in a bearing —41— positioned on bracket —26—. A crank arm —42— is secured to shaft —39— and is connected by link —43— with crank arm —38—, link —43— being indicated in dotted lines on Figure 3. I also provide a pivoted lever —44— which is connected by a link —45— to a crank arm —46— which is secured to shaft —39— so that when the lever —44— is moved about its pivot it will cause the rotation of shaft —39— which in turn through crank arm —42—, link —43— and crank arm —38— will rotate shaft —36— and move drag arm —35— up or down as desired.

30 The opposed drag —34— is of similar construction and is journaled in side —47— in a bearing —48— and is connected by a link —49— (shown in dotted lines on Figure 2) to a crank arm —50— secured to a shaft —51— which has one end journaled in bearing —41— and the other end journaled in a bearing —52— positioned in side —47—. A lever —53— is connected through a link and crank arm, not shown, to shaft —51— for imparting rotary motion thereto, such link and crank arm connection being similar to the connection described for lever —44—. By using either or both of levers —44— and —53— drags 33 or 34 or both may be brought into contact with the surface of the ice to assist in retarding the forward movement of body —1—.

35 I also provide in body —1— a plurality, in this case shown as eight, of seats —54—.

40 It will be understood that the materials of which my device is constructed may be varied as desired as may be the particular reinforcing means used to make the structure sufficiently strong to withstand any shock which it may receive in use. It will also be under-

stood that the type and design of the motor to be used on my structure may be varied depending upon the rapidity with which it is desired to propel the structure forward. It will also be understood that when the device is traveling on the ice the direction of its forward movement may be changed by the use of one of the drags 33 or 34 in lieu of the use of rudder —16—.

It will also be understood that the size and shape and association of the various parts of my structure may be varied to a very considerable degree without departing from the spirit of my invention, for altho I have shown and described a specific structure and form and association of parts as an exemplification of an embodiment of my invention I do not desire to restrict myself to the exact size, shape and arrangement of parts as various changes may be made within the scope of the appended claims.

What I claim is:

1. In a combined ice and water vehicle, a body having an upwardly curving square front end and a narrower rear end, an air propeller mounted on the rear of the body, means for rotating the air propeller, an air rudder mounted on the rear of the body, means for pivoting the rudder in its support, and opposed shoes extending approximately the full length of the under side of the body.

2. In a combined ice and water vehicle, a body having an upwardly curving square front end and a narrower rear end, an air propeller mounted on the rear of the body, means for rotating the air propeller, an air rudder mounted on the rear of the body, means for pivoting the rudder in its support, opposed shoes extending approximately the full length of the under side of the body, a crank arm pivotally mounted in one side of the body adjacent the rear end thereof for movement below and above the under surface of the body, means for pivoting the crank arm, a second crank arm pivotally mounted on the other side of the body for movement below and above the under surface of the body, and means for pivoting the last mentioned crank arm.

3. In a combined ice and water boat, a body approximately rectangular in lateral cross section and having an upwardly curving front end, a shoe extending longitudinally of the under face of the body adjacent one side thereof, a second shoe extending longitudinally of the under surface of the body adjacent the opposite side thereof, an air propeller mounted on the top of the body adjacent the rear thereof, means for rotating the air propeller, an air rudder pivotally mounted on the body adjacent the air propeller and in the rear thereof, means for pivoting the air rudder in its supports, a crank arm pivotally mounted in one side of the body adjacent the rear end thereof for

movement below and above the under surface of the body, means for pivoting the crank arm, a second crank arm pivotally mounted on the other side of the body for movement below and above the under surface of the body, and means for pivoting the last mentioned crank arm.

4. In a combined ice and water boat, a body substantially rectangular in form and having a flat bottom curved upwardly at its forward end, a runner rigidly affixed to each longitudinal edge of the bottom of the body for substantially the full length thereof, an air propeller mounted at the rear of the body and behind the center of gravity thereof, means for imparting rotary motion to the propeller, an air rudder pivotally mounted on the body and positioned to be in the path of movement of the air displaced by the propeller, means for pivoting the air rudder, a crank arm pivotally mounted in one side of the body adjacent the rear end thereof for movement below and above the under surface of the body, means for pivoting the crank arm, a second crank arm pivotally mounted on the other side of the body for movement below and above the under surface of the body, and means for pivoting the last mentioned crank arm.

5. In a combined ice and water vehicle, a body having an upwardly curving square front end and a narrow rear end, an air propeller mounted on the body, means for rotating the air propeller, an air rudder mounted on the body, means for pivoting the rudder in its support, opposed shoes extending approximately the full length of the under side of the body, and means, operable at will, for contacting the surface of the ice and adapted to retard the movement of the vehicle.

In witness whereof I have hereunto set my hand this 10th day of May, 1928.

MORRIS C. KNIGHT.
